SERVING TRAY FOR TUMBLERS OR THE LIKE

Frank De George, 103 Pleasant Ave.,
Upper Saddle River, N.J. 07458

Filed Mar. 3, 1970, Ser. No. 21,710

Term of patent 14 years

Int. Cl. D7—06

U.S. Cl. D44—10

Fig. 5.

Fig. 6.

Fig. 7.

Fig. 8.

FIG. 1 is a front elevational view of a serving tray for tumblers or the like showing my new design, in vertical position;

FIG. 2 is a top plan view thereof;

FIG. 3 is a side elevational view thereof;

FIG. 4 is a bottom plan view thereof;

FIG. 5 is a top plan view of the serving tray in horizontal position;

FIG. 6 is a bottom plan view thereof;

FIG. 7 is a front elevational view thereof; and

FIG. 8 is an end elevational view thereof.

I claim:

The ornamental design for a serving tray for tumblers or the like, substantially as shown.
